UNITED STATES PATENT OFFICE

144,454

DESIGN FOR A SANDAL

Bernard Ferrar, La Crescenta, Calif.

Application July 20, 1945, Serial No. 120,818

Term of patent 3½ years

(Cl. D7—7)

To all whom it may concern:

Be it known that I, Bernard Ferrar, a citizen of the Union of Soviet Socialist Republics, residing in the city of La Crescenta, in the county of Los Angeles, State of California, have invented a new, original, and ornamental Design for a Sandal, of which the following is a specification, reference being had to the accompanying drawing, forming a part thereof.

I claim:

The ornamental design for a sandal, substantially as shown.

BERNARD FERRAR.
